UNITED STATES PATENT OFFICE.

JOHN H. TURCOTTE, OF INDIAN ORCHARD, MASSACHUSETTS.

SPINNING OR TWISTING APPARATUS.

No. 895,701.

Specification of Letters Patent.

Patented Aug. 11, 1908.

Application filed December 26, 1907. Serial No. 408,037.

To all whom it may concern:

Be it known that I, JOHN H. TURCOTTE, a subject of the King of Great Britain, residing at Indian Orchard, in the county of Hampden and State of Massachusetts, have invented a new and useful Spinning or Twisting Apparatus, of which the following is a specification.

My invention relates to improvements in apparatus, for ring-spinning frames or twisting machines, designed to guide the yarn or thread as it passes to a yarn carrier or spindle and to put a drag on said yarn or thread, and said invention comprises in general a holder adapted to be fastened to the reciprocating ring-rail of the machine, a revolute ring or guide of peculiar construction, a notched screw cap or cover on said holder, said guide being arranged and adapted to run freely in the holder and cap, and one or more cleaners mounted on said cap, all as hereinafter set forth.

The objects of my invention are, first, to produce a comparatively light, simple and inexpensive apparatus of the class specified which is convenient, durable and economical, is adapted for any kind or grade of yarn or thread that is to be spun or twisted; second, to produce such an apparatus which runs so easily and freely as to require only a small amount of drawing power to operate it so that there is no hard pull on the strand or on the spindle, and an apparatus the use of which permits greater speed to the spindle and insures a better product and more of it; third, to utilize the draft created by the rapidly revolving spindle and bobbin to facilitate the rotation of the thread guide of the apparatus and also to remove lint, dust and dirt from the apparatus and from the yarn or thread in connection with which said apparatus is employed; fourth, to afford means for preventing any accumulation of dirt to collect between the vertical arms of said guide and the cap; fifth, to dispense with separators by making provisions for otherwise cleaning the yarn or thread as it whips out or balloons, whereby specks are removed from the same and hard places and bunches therein are smoothed out, the cleaners on the cap performing these offices, and sixth, to furnish an apparatus which not only possesses the advantages above enumerated, but as a whole is entirely practical, efficient and satisfactory.

55 I attain these objects by the means illus-

trated in the accompanying drawings, in which—

Figure 1 is a side elevation of my apparatus mounted on a ring-rail in operative relation with a spindle and bobbin, the front cleaner being omitted; Fig. 2, a sectional view of the apparatus and rail, the guide standing in a different position from that shown in the preceding view; Fig. 3, a top plan view of the apparatus alone, said guide having still another different relation to the other parts, and, Fig. 4, a side elevation of the guide.

Similar figures refer to similar parts throughout the several views.

In each of Figs. 1 and 2 a portion of an ordinary ring-rail 1 having an opening 2 for the spindle and bobbin is shown, and in the first of these views a spindle 3 together with a bobbin 4 with yarn 5 thereon appear.

My apparatus comprises three major elements, namely, a base piece or holder 6, a guide 7, and a cover or cap 8, in addition to which are one or more cleaners 9, and other auxiliary and subsidiary parts and members, all of which I will now proceed to describe in detail.

The holder is in the form of an externally screw-threaded ring which is provided on the inside at the bottom with a ball-race 10 and has two or more laterally-extending ears 11 at the base. The ears 11 have slots 12 therein for screws 13 by means of which the holder 6 is securely fastened on the ring-rail 1. These slotted ears enable the holder to be properly adjusted on the ring-rail so that said holder will be concentric with the spindle 3. A groove 14 may be made in the outside of the holder to join the slot 12 in each ear 11 to receive the head of the corresponding screw 13 when the nature of the adjustment requires. A set-nut or lock-ring 15 for the cap is placed on the threaded part of the holder. The cap 8 which is also in the form of a ring, has a depending externally screw-threaded flange which fits the aforesaid threaded part of the holder. Four notches 16, more or less, are formed in the inner edge of the cap 8, for the purpose presently to be explained. These notches may be rectangular or of any other suitable shape, but each should present a sharp corner or edge to the passing guide members. On the inside of the cap is a ball-race 17.

The guide 7 consists of a hollow shell hav-

ing several large openings 18 and several small openings 19 through the sides thereof and provided with a plurality of laterally extending supports 20, generally four in number, and with a plurality of upstanding arms 21, also generally four in number, the number of the supports and the number of the arms depending somewhat, however, on the size of the apparatus. Each support 20 has a ball-recess in the bottom and another in the top for balls 22—22 which travel in the ball-races 10 and 17 when the guide revolves. Thus it will be seen that the holder supports the guide and the cap keeps said guide in place, it being understood that in assembling the guide is first placed in the holder with the supports 20 resting on the balls 22 in the lower race and then the cap is placed on said holder around the arms 21 and screwed down until just the right amount of pressure on the balls in the two races is produced, after which the lock-ring 15 is screwed up tight against the lower edge of the cap flange to prevent the cap from becoming accidentally loosened or displaced. The parts are so proportioned that the guide fits loosely within the holder and the arms 21 fit loosely within the cap, while the passage through said guide is large enough to accommodate a full bobbin on the spindle. Each arm 21 resembles more or less closely a hook the eye 23 of which receives the yarn or thread on its way to the bobbin, which yarn or thread may be slipped into the eye through the slot 24 in the edge of said arm that is behind in the direction of rotation of the guide. These eyes may be reinforced with any suitable anti-friction material such as glass, steel, and the like, if desired. Below the eye in each arm there may be a hole or opening 25, and the vertical edges of each arm are chamfered, as shown at 26, the sharp edges being next to the inner edge of the cap 8. The chamfered edges 26 act with the adjacent corners or edges of the notches 16 to cut out the waste as it accumulates or to prevent it from accumulating at these points and to maintain the surrounding portions of the apparatus in a condition free from lint and dirt, the loosened matter being thrown out by the rapidly revolving arms and blown away by the draft produced by the rapidly revolving spindle and bobbin. Furthermore, the sharp edges of the arms offer less resistance to the air than would dull edges and cleave their way through the air, as it were, more easily.

The openings 18, 19 and 20 in the guide and its arms not only lighten the structure, but afford passages for the currents of air created by the spindle and bobbin when in motion, to the end that the motion of the guide is effected in part by the whirling air, and besides all dust and dirt are expelled by the draft through such openings so that the 65 yarn or thread is kept clean. The dust and

dirt are also blown out through the notches 16. As will be seen readily, the construction and arrangement whereby the air forces created or set in motion by the spindle and bobbin are utilized to facilitate the rotation of the guide by augmenting or assisting the pull of the yarn or thread and by serving to some extent as an anti-friction medium in which the guide revolves, and to clear said guide and the bearing parts of waste and dirt, constitute valuable features of my invention. 75

Another important and valuable feature is found in the plurality of guide hooks whereby it is unnecessary when the yarn or thread breaks, to rotate the guide in order to bring an attaching point in front of the operator, because there is always such a point in the form of one of the arms 21 in that position, consequently the reengagement of the yarn or thread with the guide is easily and quickly 85 brought about.

One or more devices that I term cleaners are adjustably mounted on top of the cap 8, there being usually three or four such devices. Each cleaner comprises a base block 27 adjustably arranged on the cap 8, and the vertical, revoluble, dentiform roller or cleaner proper 9 mounted on said block. In the present case each block 27, which lies horizontally on the cap, has a longitudinal slot 28 therein through which a screw 29 passes into threaded engagement with said cap to retain said block in place, and the roller 9 is mounted on a spindle 30 rising from the block near the front end thereof. Upon loosening the screws 29 the blocks 27 with their rollers 9 can be adjusted to bring said rollers nearer to the path described by the guide arms 21 or to move them further away from such path, as the size and quality of the yarn or thread may demand, after which adjustment said screws are again tightened. As has been stated, these cleaners take the place of separators. 100

The yarn or thread in ballooning or whipping out strikes the dentiform rollers 9 and so is freed from lumps and other imperfections and cleaned, and the rollers are rotated by the contacting yarn or thread and so kept clean themselves. 110

The operation of this apparatus as a whole 115 is similar to that of other apparatuses, including spinning-rings, in the same class, and will be clear to those skilled in the art, hence it need not be set forth herein at further length.

The construction of the apparatus is such that the adjustment of the ball-bearings can be made with great nicety and all wear thereof taken up; moreover, the assembling and separating of the parts is rendered easy and 125 convenient.

It is obvious that many changes of minor importance can be made in my apparatus without departing from the nature of my invention. 130

What I claim as my invention, and desire to secure by Letters Patent, is—

1. A spinning or twisting apparatus comprising a holder provided with a ball-race, a cap in threaded engagement with said holder and provided with a ball-race, a guide, in said holder, provided with a plurality of separate lateral supports and with a plurality of upstanding perforated arms extending above said cap for yarn or thread, and balls between said races and said supports. 55
2. A spinning or twisting apparatus comprising a holder provided with a ball-race, a cap arranged to screw on to said holder and provided with a ball-race, a lock-ring in threaded engagement with the holder below said cap, a guide, in said holder, provided with a plurality of separate lateral supports and with a plurality of upstanding perforated arms extending above said cap for yarn or thread, and balls between said races and said supports. 65
3. The combination, in an apparatus of the class described, with a holder, and a cap open in the center and having a notch in its inner edge, on the holder, of a hollow guide revolvably mounted in said holder and provided with a plurality of upstanding arms for yarn or thread extending through the cap into contiguity to the notched edge of said cap to produce a shearing effect. 75
4. The combination, in an apparatus of the class described, with a holder, and a cap open in the center and having its inner edge notched, on the holder, of a hollow guide revolvably mounted in said holder, said guide having perforated sides and being provided with a plurality of upstanding arms for yarn or thread extending through said cap into contiguity to said notched edge of the cap to produce a shearing effect. 80
5. The combination, in an apparatus of the class described, with a stationary holder and a stationary cap thereon, of a hollow guide revolvably mounted in said holder and provided with a plurality of upstanding arms for yarn or thread extending above said cap, the vertical edges of said arms being chamfered. 85
6. The combination, in an apparatus of the class described, with a holder, and a cap open in the center and having its inner edge
- notched, on the holder, of a hollow guide revolvably mounted in said holder and provided with a plurality of arms for yarn or thread extending into contiguity to said notched edge of the cap to produce a shearing effect, the upstanding edges of said arms being chainfered. 90
7. The combination, in an apparatus of the class described, with a holder, a cap on said holder, and a revoluble guide in the holder provided with an arm which extends above said cap, said arm having an eye therein the axis of which is radial to the center of the holder, for yarn or thread, of a cleaner mounted on the cap adjacent to the path of travel of said arm. 95
8. The combination, in an apparatus of the class described, with a holder, a cap on said holder, and a revoluble guide in the holder provided with arms which extend above said cap, said arms having eyes therein the axis of which are radial to the center of the holder, for yarn or thread, of a rotatable cleaner mounted on the cap adjacent to the path of travel of said arms. 100
9. The combination, in an apparatus of the class described, with a holder, a cap on said holder, and a revoluble guide in the holder provided with arms which extend above said cap, said arms having eyes therein the axes of which are radial to the center of the holder, for yarn or thread, of a rotatable dentiform cleaner mounted on the cap adjacent to the path of travel of said arms. 105
10. The combination, in an apparatus of the class described, with a holder, a cap on said holder, and a revoluble guide in the holder provided with arms which extend above said cap for yarn or thread, of a cleaner mounted on the cap adjacent to the path of travel of said arms, and means to adjust said cleaner relative to said path. 110
11. The combination, in an apparatus of the class described, with the cap of the apparatus, of a cleaner consisting of a base block adjustably held on said cap, and a dentiform roller loosely mounted on said block. 115
